UNITED STATES PATENT OFFICE.

CHARLES SPIRO, OF NEW YORK, N. Y.

TYPE-WRITER.

SPECIFICATION forming part of Letters Patent No. 620,808, dated March 7, 1899.

Application filed April 9, 1897. Serial No. 631,437. (No model.)

To all whom it may concern:

Be it known that I, CHARLES SPIRO, a citizen of the United States, residing at New York, in the county of New York, State of New York, 5 have invented certain new and useful Improvements in Type-Writers, of which the following is a specification, reference being had therein to the accompanying drawings.

This invention relates to improvements in 10 type-writers; and among the objects in view is to provide simple, positive, and convenient margin-controlling devices whereby marginal notes or folio-numbers may be readily printed outside of the ordinary left-hand margin of the printed page; also, to provide similar means under positive convenient control by key-lever for printing matter beyond the established right-hand margin or line end on the printed page when desired and to provide 15 for the automatic return to the established line end. Furthermore, it is designed to adapt the type-writer for a convenient and rapid change from the ordinary step-by-step feed to the jump-feed or tabulating and column feed of the carriage, whereby solid or continuous printed matter may be readily changed to tabulated work on the printed page.

In this invention I have also provided 20 means for automatically locking the type-bars against making an impression upon the page when the carriage has reached an established line end, while at the same time this function of the machine is under control of the operator in that it may be temporarily set aside or varied.

While I have provided a type-writer with mechanism for performing the above-mentioned functions, I have also devised such a 25 construction, arrangement, and connection of said mechanism that these functions may be brought out by the simple manipulation of a single key at the keyboard of the machine.

Other objects and advantages of the invention 30 will appear in the following description, and the novel features thereof will be particularly pointed out in the claims.

Referring to the drawings, Figure 1 is a 35 plan, and Fig. 2 is a substantially central vertical longitudinal section, of the principal parts of a type-writer embodying my invention. Fig. 3 is a diagrammatic perspective

of the mechanism employed for controlling the carriage-feed for the purpose of printing marginal notes, locking the keyboard at a pre-determined margin, and changing from step-by-step to jump feed and the connection of such mechanism with a single key. Figs. 4, 5, and 6 illustrate type-bar bearings and brackets, the latter figure representing in 40 perspective the tool for adjusting the bearings. Figs. 7 and 8 represent in perspective and vertical sections, respectively, the ribbon-spool and its adjuncts. Figs. 9 and 10 represent in substantially central vertical section and rear elevation the ribbon-shift mechanism.

Like letters refer to like parts in all the figures of the drawings.

A represents the key-levers, which are connected by ligaments B with the type-bars C of the machine. Each of the type-bars is provided with a transverse bearing-shaft C', the ends of which are coned, as shown, and take bearing at one end in the wall of a bracket D and at the other end in a cone-bearing E, screw-threaded in the opposite wall of the bracket. The bearing E is slotted, as at E', for the reception of a lever F, one end of which is tapered to fit the slot E', as at F', and the other end of which tool is tapered and bent, as at F'', to fit the slot E' and to be placed within the slot when the same is inaccessible to the opposite end F' by reason of the position of the slot. In the completed machine 55 the type-bar brackets are arranged very closely together, rendering it difficult to get access to the adjustable bearing of the type-bar. Now by providing the cone-bearing with one or more slots or grooves the same is accessible for the operation of a tool for adjusting the bearing; but the bearings being so closely assembled in the machine the tool must necessarily be thin, and therefore if entered in the slots flatwise it would readily 60 bend; but being tapered and entered edge-wise greater strength is given to the tool, while at the same time accessibility to the parts is retained.

The base of the bracket is provided with 100 two lugs D' and an aperture D'' for the reception of the bracket-retaining screw D', Fig. 1, by which the brackets are secured to the bridge G, the lugs D' resting in the groove G'

of the bridge. Instead of inserting pins in the base of the bracket to perform the function of the lugs B', I form them by forcing down the metal of the base by suitable dies, forming depressions D¹X, as shown by dotted lines in Fig. 5. This gives a cheaper and stronger construction than forming the lugs of separate pieces. To prevent the spreading of the walls of the bracket in an adjustment of the type-bar bearings, I employ a screw-threaded tie-bar D⁵, which is threaded into the walls at each end, cut off flush with the outer surface of each wall, and then is set against withdrawal and against rotation by the formation with any suitable tool of a depression D⁴, extending across the rod and for a distance beyond the same into the surface of the wall, as clearly illustrated in Fig. 4. This depression D⁴ necessarily mars the threads in the wall and on the rod, thereby locking the latter against rotation, while the adjacent threads seated in the wall prevent the spreading of the walls. This construction is preferable to countersinking the outer faces of the walls and riveting or upsetting the ends of the tie-rod within the countersink, as this work has a tendency to bend the rod or otherwise throw the walls out of parallelism. The screw-threaded rods permit easier, more accurate, and cheaper assembling of the parts.

In referring again to the type-bar bracket D it will be noticed, more clearly in Fig. 1, that the shafts C' of the several type-bars mounted in a single bracket are arranged out of parallelism with each other. The object of this arrangement is to bring the type of each of the three bars assembled in a single bracket to one common printing-point. The shaft of the central bar is practically parallel with the base of the bracket, while the shafts of the other bars are at an angle to a vertical line bisecting the base parallel with the side walls of the bracket. It will be noted that there are two rows of brackets on the bridge G and that the rear row of brackets have each two type-bars therein, while the front row has three type-bars in each bracket. Now by the proper disposition of the angles which the shafts of the several type-bars in a front and an adjacent rear bracket occupy all of the five type-bars are brought into or between the same pins W' of the bar-lock W of the machine. By this construction less dependence is placed upon the sidewise springing of a type-bar when it enters the bar-lock and heavier material may be employed for the bars.

H is the universal bail of the machine and from it projects a ribbon-guide I, whereby at the depression of each key-lever of the machine the ribbon is carried under the type and returned with the guide, so as to expose the printed character. The oscillation of the ribbon-guide serves through the medium of the pawl I' to operate a ratchet J, Figs. 2, 9, and 10, mounted on a shaft J', bearing at each end a pinion J². The shaft is mounted in an oscillating block J³, carried by a pivot J⁴,

seated in the standard J⁵, upon which the spools K and their shaft K' and gears K² are mounted, all as clearly shown in Fig. 10. It will be noted that when the block J³ is inclined in one direction the pinion J² meshes with the spool-gear K² at one side of the standard, and vice versa.

L L' represent latches pivoted on the standard J⁵ and adapted to take under projections J⁶ at each side of the block J³, for the purpose of locking a pin J² in mesh with a gear K². Above the pivots of the latches each is provided with an arm L², and these arms are connected by a coiled spring L³, the purpose of which is to force one latch quickly under a projection J⁶ as soon as the opposite latch is released from an opposite projection, the release being occasioned by an oscillation of the block J³ and the operation of an arm M', projecting from a rock-shaft M, mounted in bearings projecting from the standard J⁵. From the rock-shaft M there is projected a spring M², which terminates in a socket of the screw J⁷, which secures the detent J⁸, operating on the ratchet J. Of course the spring M² may be otherwise operatively connected with the block J³. Now it will be seen that when the rock-shaft M is oscillated it first brings the arm M' into contact with the latch or with a projection thereon, as shown in Fig. 9, and forces said latch from beneath a projection J⁶ on the block J³, Fig. 10. During the movement of the arm M' in thus releasing the latch the spring M² has been put under tension, which oscillates the block, the opposite latch having in the meantime been moved under the opposite projection J⁶ by the coiled spring L³.

The oscillation of the rock-shaft M is produced by mechanism operating against the double arm M³, one of the two ends of which rests above one of the spools and the opposite end above the other.

Each of the spools K has a substantially radial slot K³ in each wall thereof, and in the slot rests a bar K⁴, to which the ribbon N is connected in any suitable manner. In this instance a hook N' is employed. At each end of the bar K⁴ is secured a finger K⁵. Now it will be noted that when the end of the type-ribbon is reached the unwinding movement of the spool continues through the operation of the pawl I', ribbon-guide I, ratchet J, pinion J², and pawl K², and the bar K⁴, with the fingers K⁵, is gradually brought outwardly from the center of the spool toward its periphery in the slots K³ until the fingers K⁵ come into contact with one end of the double arm M³ of the rock-shaft M, and said fingers continue movement about the center of the spool, forcing the arm M³ to move with them until the arm M' and spring M² have accomplished an oscillation of the block J³, which carries the opposite pinion J² into mesh with the gear of the empty spool, which then begins to wind ribbon upon the spool which caused the reversal of ribbon-feed. Fig. 10

shows the parts in the position assumed at the instant that the fingers have caused a meshing of a pinion with the gear of the empty spool, and it is apparent that substantially the entire length of the ribbon has been employed.

The margin-work of the machine is controlled by margin-gages pivotally mounted so as to be thrown out of the path of the carriage by means of a key and suitable connecting mechanism.

Referring to Fig. 3, O represents a gage-bar with a movable gage O' for determining the left margin of the printed page, and P represents a gage-bar carrying a gage P' for determining the right margin of the printed page. Each of these bars is provided upon its face with a graduated scale with suitable numerals having a desired fixed relation with the ordinary scale usually provided on the paper carriage or frame, or on both, for determining the printing-point and the margin-line. The numerals on the left-margin scale on gage-bar O may extend from zero to forty-five graduations and those of the right-margin-gage bar P from eighty-two to forty-four of the paper-carriage scale. In other words, the graduations of each of the margin-gage bars may extend from the extremes to any distance along the graduations of the paper-carriage scale which may be desired, the essentials to perfect work being that a given indication on any one of the scales for the gages shall coincide with the same graduations of the paper-carriage scale. The left-margin gage O' consists of a metal plate embracing the rear edge and the two sides of the bar O with a projection O² adapted to contact with any desirable fixed part of the paper-carriage. The gage is also provided with a pawl O³, which coöperates with teeth O⁴, formed on the front edge of the bar O. The pivot O⁵ of the pawl is extended to form a pawl-releasing handle, and the gage itself is provided with handle O⁶, against which the handle O⁵ may be moved to release the pawl and permit of changing the position of the gage on the bar. The bar O is provided with journals O⁷ O⁸, which are mounted in brackets O⁹ and O¹⁰, formed on or in a stationary part of the machine. The bar P for the right-margin gage is similarly constructed and has a journal P² pivotally seated in a bracket O¹¹. Between the end of the bar and the bracket there is a coiled spring P³, whereby the bar may be reciprocated toward the bracket and returned by the spring. The opposite end of bar P is bored to receive the journal O⁸ of the bar O and a pin P⁴, which is mounted in the end of the bar O. This connection of the bar P with the bar O transmits a tilting movement of the bar O to the bar P and at the same time permits the above-mentioned reciprocation of the bar P for the purpose of locking the universal bail and the keyboard at the end of the printed line, as hereinafter described. The gage P' embraces the bar P and carries a spring-detent engaging

with the teeth P⁶ of the bar. There is mounted upon the gage a hook P⁷, which is normally held by a spring P⁸, projecting beyond the face of the bar and in line with any desired lug or fixed portion on the carriage of the machine. The yielding pivoting of the hook P⁷ permits the same to be moved by the lug upon the carriage when the same has passed beyond the right-margin gage for the purpose of writing additional letters at the right margin of the sheet. The lug will pass the gage when the bar P is slightly tilted, which permits writing beyond the margin-gage, while the return movement of the carriage simply moves the hook to one side by the engagement of the lug with the rounded face thereof.

Upon the bar O there is fixed an arm Q, which is designed to coöperate with the teeth Q' of a jump-feed rack-bar Q², supported in any desired manner by and traveling with the paper-carriage. For instance, the jump-feed rack Q² is supported beneath a plate Q³, projecting from or secured to the carriage, as clearly shown in Fig. 2. The bar Q² is held to the plate Q³ by screws Q⁴, one at each end, threaded in the bar or lugs Q⁵ thereon, which serve to space the bar from the plate.

Now it will be seen that when the left-margin gage is set at a desired point the carriage will be stopped at that point by contact with the pawl O³ of the gage and the printing of the page will begin at a predetermined point. Now by tilting the bar O in the direction of the arrows, Fig. 3, the pawl O³ of the gage O' may be raised out of the path of the projection on the carriage and the latter may be moved so as to impress folio-numbers or other matter outside of the left margin.

When it is desired to indent the printed matter or to produce a hanging indentation, then the projection O² of the gage O' is brought into the path of the carriage by a partial tilting of the bar O, when the indentation is produced in the printed matter.

For the purpose of tilting the gage-bars the bar O is connected by a link R with a lever R', pivoted to a fixed part of the machine and connected beyond its pivot by a ligament R² with a key-lever R³, mounted in the frame of the machine like the remaining key-levers, but outside of and so as not to effect the universal bail of the machine or the feed mechanism operatively connected therewith. The key-lever R' terminates in a key marked "M. R.," meaning margin-regulator.

The right-margin gage having been adjusted, as described, by moving the same along the bar P, which movement is permitted by the spring-detent P⁵, will, by contact with a projection on the carriage, draw the bar P along with the carriage, compressing the spring P³, and lock the keyboard of the machine against further printing by the mechanism which I will now proceed to describe.

Depending from the lower face of the bar P is a wedge S. Projecting upwardly through

the base of the machine is a rod S', enlarged at its upper end, forming a head, under which the wedge or block S may pass under certain conditions. The lower end of the rod S' is 5 pivotally connected with the universal bail H, so that as the bail oscillates the rod S' is reciprocated up and down. It is clear that the reciprocation of the rod S' takes place upon the depression of each and every key of the key-board and of the spacing-bar of the machine. The margin-regulator key, however, is an exception in this regard. It therefore follows that when the gage-bar P is drawn by the carriage in the direction indicated by the arrows 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

There still remains another function to be performed, primarily, by the margin-regulator key, and that is the change from a step-by-step movement of the carriage for plain printing to a jump-feed for the same for tabulated work. This function not only involves the tilting of the bar O and the arm Q thereon, so as to contact with the jump-feed rack Q' Q'', but it requires, in addition, the throwing out 30 of operation of the step-by-step feed mechanism. This is accomplished by the following devices: Upon the bed of the machine there is a lever T, pivoted at T' and terminating in a finger-piece T'', having two openings T''³, either of which may encircle a retaining-stud T', seated in the base. Beyond its pivot the lever T is formed with ears T'', in which is pivoted a secondary lever U, which is projected over and beyond a pin V, projecting from the 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

escapement-dog V' of the step-by-step feed mechanism. These dogs are pivoted at V'' and held normally by a spring V''³ in an upward position on their pivot, wherein they are in position to operate upon the carriage-feed rack. The lever U is bent at a right angle and passed through a slot R' in the lever R'. When the parts thus described are in the position shown in Fig. 3, the machine is in condition to feed step by step. When, however, the finger-piece T'' of the lever T is raised and the lever shifted rearwardly, so as to make the opposite opening T'' rest upon or about the pin T', then the free end of the lever U is brought over the pin V of the dogs V', so that when the margin-regulator key is depressed the free end of the lever U and the feed-dogs are also depressed and at the same time the

bar O and its arm Q are oscillated and the carriage is fed from tooth to tooth of the jump-feed rack, and thereby tabulated printed matter is produced by the machine.

The advantage of constructing the margin-gage bar in divisions is important. One division may perform functions impossible for another division, while both or all divisions are capable of community of action for other functions. In the form shown the division O, while capable of oscillation to bring the arm or stop Q in contact with the jump-feed rack Q'', is preferably incapable of reciprocation, so as to form a solid abutment for this form of feed. On the other hand, the division P of the margin-gage bar by its capability of reciprocation is enabled to carry and apply the lock for the keyboard and also by its capability of oscillation to free the gage P' from the carriage at the same time that the gage O' is freed for the purpose, for example, of starting the next line with a folio numeral outside of the predetermined left margin, which is determined by the pawl O'.

What I claim is—

1. The combination with a keyboard and a carriage of a type-writer, of a universal bail, a device directly connected to said bail, a longitudinally-movable gage-bar engaged by the carriage for locking said device at the end of a line, and means for releasing said device; substantially as specified.

2. The combination with a keyboard and a carriage of a type-writer, of a universal bail, a device directly connected to said bail, a longitudinally-movable gage-bar actuated by the carriage to engage said device, and means for moving said bar in two directions to lock and release the universal bail; substantially as specified.

3. In a type-writer, a divided gage-bar having a non-reciprocatative, oscillatory part, and a part which is mounted for longitudinal movement and provided with a locking device, means for moving said latter part of the gage-bar to render active said locking device, and a movable member coöperating with said non-reciprocatative part of said gage-bar; substantially as specified.

4. In a type-writer, an oscillating divided gage-bar, one portion of which is mounted for longitudinal movement independently of the other portion and provided with a locking device, means for actuating said longitudinally-movable portion of the bar to render active said locking device, and a movable member coöperating with said non-reciprocatative part of said gage-bar; substantially as specified.

5. In a type-writer, a divided gage-bar, one part thereof having movement independent of the other part, in combination with devices separately coöperating with said parts and carried by a movable part of the machine; substantially as and for the purposes set forth.

6. In a type-writer, a divided gage-bar mounted for oscillation as a whole and for the

longitudinal movement of a part thereof, a key-lever for oscillating said bar, a locking device carried by a part of said bar, means for actuating the longitudinally-movable portion of said bar, and a movable member co-operating with the oscillatory portion of the bar; substantially as specified.

5 7. A gage-bar mounted for reciprocation and provided with a wedge or block in combination with keyboard-locking mechanism connected directly with a universal bail; substantially as specified.

10 8. A gage-bar provided with means for locking a keyboard through a direct connection with a universal bail; substantially as specified.

15 9. A gage-bar provided with means directly connected with the universal bail for locking a keyboard through the medium of a carriage, and a pivoted key-lever in the keyboard and independent of said universal bail and suitably connected with the gage for releasing the keyboard; substantially as specified.

20 10. In a type-writer, the combination with a carriage, of a divided gage-bar a part of which is reciprocative, an adjustable gage upon each division of said bar, a locking device carried by the reciprocative portion of said bar, and a movable member co-operating with the reciprocative part of said gage-bar; substantially as specified.

25 11. The combination of a tiltable gage-bar, of a left-margin gage having two relatively-fixed projections, the one for a standard margin and the other for indenture, both mounted upon and adjustably movable along said gage-bar; substantially as specified.

30 12. The combination with a tiltable gage-bar, of a left-margin gage having two relatively-fixed projections, the one for a standard margin and the other for indenture, both mounted upon and adjustable along said gage-bar, and means for tilting said bar terminating in a key at the keyboard of the machine; substantially as specified.

35 13. A gage-bar mounted for oscillation and provided with an arm for co-operation with a jump-feed rack-bar when the gage-bar is oscillated, and means connected with the gage-bar for oscillating the same and for simultaneously throwing the feed-dogs of the machine out of operation; substantially as specified.

40 14. A gage-bar mounted for oscillation and carrying a jump-feed arm or stop, a lever for oscillating the gage-bar, a secondary lever connected therewith, and means for putting said secondary lever into and out of operative relation with the feed-dogs of the type-writer; substantially as specified.

45 15. A longitudinally-movable gage-bar mounted for oscillation, an oscillatory part of said bar mounted against longitudinal movement and connected with a key-lever and key, an adjustable right-margin gage carried by said longitudinally-movable bar and adapted to move said bar when engaged by a carriage, a yielding projection normally in the path of

the carriage and movable therefrom by oscillation of the entire bar, and a device adapted to co-operate with said oscillatory part of the bar; substantially as specified.

50 16. A longitudinally-movable gage-bar mounted for oscillation, an oscillatory part of said bar mounted against longitudinal movement, a key-lever located in a keyboard independently of a universal bail and connected to said oscillatory part of the bar for the oscillation thereof, an adjustable right-margin gage having a projection yielding in one direction and mounted on said bar whereby engagement with a carriage will reciprocate one part of the bar in one direction and said projection may be released from the carriage through an oscillation of the entire bar by means of said key-lever, and a device adapted to co-operate with said oscillatory part of the bar; substantially as specified.

55 17. As a means for throwing the feed-dogs of a type-writer into and out of operation, a lever pivoted upon and carried by a secondary lever adapted to be changed in position, and means for vibrating the first-mentioned lever; substantially as specified.

60 18. A divided gage-bar mounted for oscillation as a whole and for reciprocation in a part, the latter being provided with a spring for its movement in one direction and with a gage projecting into the path of an extraneous moving part of the machine for its movement in the opposite direction; substantially as specified.

65 19. A gage-bar constructed for oscillation and for reciprocation and provided with a gage having a yielding hook or projection, a returning-spring, and a depending block or wedge in combination with a flanged or headed rod connected with the universal bail of a type-writer; substantially as specified.

70 20. In a type-writer, a divided gage-bar mounted for oscillation as a whole and for reciprocation in a part, a portion of said bar being provided with a projection adapted to enter and move in a recess formed in an adjacent part, a locking device carried by the reciprocative portion of said bar, and means for reciprocating said portion of the bar; substantially as specified.

75 21. The combination with a tiltable gage-bar, of a margin-gage provided with a longitudinally-adjustable stop for establishing a standard margin and also provided with an adjustable indenture-stop adapted to move with said standard-margin stop and into operative position when the bar is tilted; substantially as specified.

80 22. The combination with a tiltable gage-bar, of a margin-gage provided with a longitudinally-adjustable stop for establishing a standard margin, an adjustable indenture margin-stop carried by said gage and lying in a plane below said standard-margin stop, and means for tilting said bar to bring the indenture-stop into operative position; substantially as specified.

23. A margin-gage comprising a clip adapted to surround a toothed gage-bar and a spring having a tooth intermediate of its ends and held at opposite ends within said clip so as to bear against said toothed bar; substantially as specified.

24. A margin-gage comprising a clip adapted to slide upon the gage-bar, a hook projecting into the path of the carriage with a straight face at an angle to said bar, and a spring to retract the movement of said hook when the curved face is engaged by a moving member; substantially as specified.

25. A lever for engaging and holding out of operative relation the dog mechanism of a type-writer, the same being pivoted and provided at one end with means for engaging said dog mechanism and at its other end with oppositely-located means to engage a stationary part of the type-writer and hold said lever in its shifted positions; substantially as specified.

26. A mechanism for engaging the dog mechanism of a type-writer comprising a horizontally-disposed lever pivoted to the frame of a type-writer, a secondary lever pivotally mounted at one end of said horizontally-disposed lever, and an extension at the opposite end of the latter lever provided with apertures adapted to fit over a projection located upon a stationary part; substantially as specified.

27. A locking mechanism for the universal bail of a type-writer comprising a pivotal bail, a vertically-extending rod pivoted at one end thereof and provided with a head, and a reciprocating gage-bar provided with a projection adapted to engage said head when the bar is reciprocated by the contact therewith of a traveling carriage; substantially as specified.

28. A gage-bar mounted for oscillation and reciprocation and composed of parts joined so as to oscillate in unison, one of said parts being mounted to reciprocate upon an extension from the other, a projection secured upon a stationary part of the type-writer, and a coil-

spring extending between the reciprocative part of said bar and said stationary part; substantially as specified.

50

29. A gage-bar mounted for oscillation and reciprocation and composed of two parts joined together so as to oscillate in unison, one of said parts being mounted to reciprocate upon an extension from the other part, and means to hold said reciprocating part in its position nearest the adjacent part; substantially as specified.

30. A divided gage-bar mounted for oscillation as a whole and for the reciprocation of a part thereof, one of said parts being mounted to reciprocate upon an extension from the other part, said reciprocating part being provided with a hook or wedge adapted to engage means for locking the type-bars against movement, and means for holding said reciprocating part and hook normally out of contact with said locking means; substantially as specified.

60

65

31. The combination with a keyboard and carriage of a type-writer, of a universal bail, a device directly connected to said bail, a movable wedge carried by a longitudinally-movable gage-bar and adapted to lock said device at the end of a line, said movable wedge being operated in the movement of the carriage, and means for releasing said wedge from said device; substantially as specified.

75

32. The combination with a keyboard and carriage of a type-writer, of a universal bail, a device directly connected to said bail, a movable wedge carried by a longitudinally-movable gage-bar and adapted to lock said device at the end of a line, said movable wedge being operated in the movement of the carriage, means for releasing said wedge from said device, and a spring to move said wedge in one direction; substantially as specified.
